DESIGN FOR A WATER STILL

Walter Van Guilder, River Forest, Ill., assignor to Precision Scientific Co., Chicago, Ill., a corporation of Illinois

Application December 18, 1942, Serial No. 109,063

Term of patent 3½ years

To all whom it may concern:

Be it known that I, Walter Van Guilder, a citizen of the United States, residing at River Forest, in the county of Cook and State of Illinois, have invented a new, original, and ornamental Design for a Water Still, of which the following is a specification, reference being had to the accompanying drawing, forming part thereof.

The figure is a perspective view of a water still embodying my new design.

I claim:

The ornamental design for a water still, substantially as shown.

WALTER VAN GUILDER.
